UNITED STATES PATENT OFFICE

160,322

RAZOR

George Douglas Jones, Los Angeles, Calif., assignor to Reelshav Corporation, Los Angeles, Calif., a corporation of California

Application June 17, 1949, Serial No. 3,355

Term of patent 14 years

(Cl. D22—3)

To all whom it may concern:

Be it known that I, George Douglas Jones, a citizen of the United States of America, residing at Los Angeles, in the county of Los Angeles and State of California, have invented a new, original, and ornamental Design for a Razor, of which the following is a specification, reference being had to the accompanying drawings, forming a part thereof.

Figure 1 is a perspective view, showing my new design for a razor.

Figure 2 is a side elevation of my razor.

Figure 3 is a top plan view.

Figure 4 is a rear elevation.

I claim:

The ornamental design for a razor, substantially as shown.

GEORGE DOUGLAS JONES.
